UNITED STATES PATENT OFFICE.

JOHN KEVAN, OF ALLEGHENY, PENNSYLVANIA.

DESIGN FOR A HANGING BANNER.

SPECIFICATION forming part of Design No. 20,234, dated October 21, 1890.

Application filed September 15, 1890. Serial No. 365,099. Term of patent 3½ years.

To all whom it may concern:

Be it known that I, JOHN KEVAN, a citizen of the United States, residing at Allegheny, in the county of Allegheny and State of Pennsylvania, have invented and produced a new and original Design for Banners, of which the following is a specification, reference being had to the accompanying drawing, forming part thereof.

5 My invention consists of a hanging banner. To the lower edge of the banner is attached a number of small bells. The surface of the banner near its upper end is ornamented by having thereon a representation of a butterfly or other ephemera with outspread wings, the same being in different colors. On the

same side of the banner and a little distance below the colored representation of an insect or butterfly is a monographic print or drawing of an exposition or other building.

Having thus described my new design, what I claim is—

The design for a hanging banner having on its surface the ornamentation shown and described.

In testimony whereof I have hereunto set my hand this 25th day of August, A. D. 1890.

JOHN KEVAN.
